BED SPRING AND MATTRESS
CONSTRUCTION

Frank Riemer and Gerald Terence Dobie,
Chicago, Ill., assignors, by mesne assignments,
to Burton-Dixie Corporation, Chicago, Ill., a
corporation of Delaware

Application August 16, 1930. Serial No. 475,682

2 Claims. (Cl. 5—351)

Our invention relates to spring-mattresses, bed-springs, cushions, etc., and concerns more particularly the attachment of the fabric-covers thereon so that they may at all times present a pleasing and attractive appearance.

While the invention is not limited or restricted to such specified employment, it is of distinct advantage when used in association with such coverings having padded sides or boxings, in that it retains such boxing or sides in a condition to maintain their agreeable and prepossessing form and fashion.

To enable those acquainted with this art to understand the invention fully, both from structural and functional standpoints, in the accompanying drawing, forming a part of this specification, a present, preferred embodiment of the invention has been illustrated in detail, and, for simplicity, like reference numerals have been employed throughout the views to designate the same parts.

In this drawing:—

Figure 1 is a fragmentary, vertical section through a corner portion of a padded spring-mattress on line 1—1 of Figure 2; and

Figure 2 is a horizontal section on line 2—2 of Figure 1.

Referring to this drawing, which presents only a very small part or corner portion of a spring-mattress, it will be perceived that the structure includes a spring-assembly, characterized as a whole 11, which may be of any approved or satisfactory type, and which, in the present instance, includes a large number of erect or vertically-disposed, hour-glass spiral-springs 12, 12, the top and bottom end-coils of which are jointed together by any appropriate style of connecting means 13, 13, such spring-assembly around its upper and lower margins or edges having border-wires 14, 14, connected in any convenient way to the top and bottom convolutions of the marginal springs.

Spring structures of this character and employed for this purpose are all known in the art and the one shown in the drawing is presented merely as an example, the invention, and the advantages accruing from its employment, not being confined to any particular form or style of spring-assembly but relating more especially to the fabric-cover about to be described and its manner of attachment to or association with such spring construction.

Such cover comprises a padded top 15 and a similar bottom 16 with suitable, resilient filling 17 between outer and inner fabric sheets 18 and 19

and a quilted or tufted side or boxing 21 extended all of the way around the structure and composed of outer and inner fabrics 22 and 23, intervening filling or padding 24, quilting or tufting stitching or ties 25, 25, and roll-edges 26, 26.

In order to attach such cover to the spring-assembly to hold its sides or boxing properly stretched lengthwise to prevent sagging or other unsightly characteristics, and to keep the edges of the cover in correct register with the edges of the spring structure, at each corner, just inside of and overlapping the inner fabric 19, a substantially triangular shaped piece of fabric 27 is fastened, as by stitching, along its two edges 28 and 29 to the cover, thus forming between itself and the adjacent fabric, 19 a three-sided pocket open along one diagonal edge 31.

In the present instance, the two margins of each three-sided pocket fabric member 27 are stitched to the inner side of the top fabric 18 and also to the inner fabric 23 of the side boxing and it is not ordinarily fastened to the fabric 19, the securing to the cloth 23, however, being capable of omission in some instances and in other cases it may be desirable to stitch to the fabric 23 and not secure to the fabric 18.

In applying the cover to the spring-assembly, it is temporarily pulled or stretched sufficiently to fit the top or bottom coil, as the case may be, of the corresponding corner-spring 12, and the part of the border-wire thereat, into such pocket, so that thereafter such pocketed parts of the spring-assembly hold the cover properly taut lengthwise the boxing, both longitudinally and transversely of the structure, to preclude the presence of wrinkles, undue fullness, etc. and to assure correct alignment or register of the edges of the cover and spring-assembly.

Thus the cover is securely and fitly held in place by means simple in construction and provided at relatively small cost, since it has been found that it is necessary and desirable to employ such pockets at the corners only, thus allowing the full lengths of the four parts of the boxing, along the sides and ends of the structure, to be made sufficiently tense and strained to accomplish the desired result.

Where the padded boxing extends around the corners, there is the tendency for the puffiness or fullness of the quilting to be flattened out, thus losing in a measure the pleased appearance which the quilting or tacking is intended to give.

To overcome this undesirable propensity, upright, narrow, spaced tucks 127 are taken in the inner fabric 23 around its corner portions, such

tucks constituting reenforcing or stiffening ribs which absorb the fabric fullness and which aid in maintaining the quilted or tacked, padded boxing in proper puffed condition, and, in some instances, such tucks 128, preferably spaced apart farther, are used along the sides or ends of the structure for a comparable purpose.

With this improved construction, the corner pockets and ribs co-operate in effective manner to keep the cover in proper place on the spring-assembly and to preserve its pleasing form at all times.

Although we have illustrated and described our invention as exemplified in a spring-mattress the top and bottom of which are alike, rendering the structure subject to easy reversal or turning over for use with either side up, it is to be borne in mind that the invention is equally applicable for satisfactory and efficient employment in bed-springs, seat-cushions and the like, and it should be remembered that the invention is not necessarily limited and restricted to the precise and exact details of structure presented and that these may be more or less modified without departure from the fundamental principles underlying the invention, the properties and characteristics of which are set out in the appended claims, and without the loss or sacrifice of any of its material or substantial benefits and advantages.

30 We claim:

1. In a structure of the character described, the combination of a spring-assembly, and a

fabric-cover therefor having a top and a padded boxing for the sides and ends thereof, said boxing comprising an outer fabric, an inner fabric, padding between said fabrics, and means securing said fabrics together at intervals through said padding, said inner fabric being provided with spaced upright fabric-absorbing stiffening tucks therein at the corners of the structure to maintain the puffed appearance of the outer fabric at the corners.

2. In a structure of the character described, the combination of a spring-assembly having upright spiral-springs, and a cover for at least the top, sides and ends of said assembly having a top and a boxing for such sides and ends and substantially triangular-shaped pieces of fabric beneath said top at the insides of the corners of the cover, each with two edges attached to the cover and the other edge free to provide a pocket accommodating the top coil of the corresponding corner spring, said side and end boxing comprising an outer fabric, an inner fabric, padding between said fabrics, and means securing said fabrics together at intervals through said padding, said inner fabric having spaced upright fabric-absorbing stiffening tucks therein at the corners of the structure to maintain the puffed appearance of the outer fabric of such boxing at the corners of the structure.
